United States Patent

Des. 236,650
Patented Sept. 2, 1975

236,650

LAMP

George F. Ritter, Jr., 3701 Dewlawn Drive,
Toledo, Ohio 43614

Filed Oct. 11, 1973, Ser. No. 405,308

Term of patent 14 years

Int. Cl. D26—05

U.S. Cl. D48—20 F

The figure is a perspective view of a lamp, showing my new design, the opposite side being identical with the omission of the clamp.

The lamp bulb and socket are shown in broken lines for illustrative purposes only.

I claim:

The ornamental design for a lamp, substantially as shown.
